(57) **CLAIM**

The ornamental design for an intelligent digital multimeter, as shown and described.

DESCRIPTION

FIG. 1 is a perspective view of an intelligent digital multimeter, showing my new design.

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top view thereof; and,

FIG. 8 is a bottom view thereof.
